UNITED STATES PATENT OFFICE.

PIERRE FRANÇOIS DUFOUR, OF PARIS, FRANCE.

Brake for Railway-Trains.

1,352,586.

Specification of Letters Patent. Patented Sept. 14, 1920.

Application filed April 29, 1919. Serial No. 293,565.

To all whom it may concern:

Be it known that I, PIERRE FRANÇOIS DUFOUR, citizen of the Republic of France, residing at 24 Rue D'Aumale, Paris, in the 5 Republic of France, have invented new and useful Improvements in Brakes for Railway-Trains, of which the following is a specification.

This invention has for its object to provide 10 an improved braking apparatus for railway trains of the kind in which the braking action is effected by taking advantage of the momentum of the cars, the brakes being operated by the buffers or other members when the cars crowd one upon another.

An important feature of the improved 15 braking system resides in that the brake operating members may be connected to the buffers on one hand and to the draw bars or like members on the other hand and combined with a control box operated by the engine driver and by means of which the brake operating members can be connected with either the buffers or the draw 20 bars, so that in one position (forward travel) the brakes are set by the buffers and in the other position (backward travel) the brakes are set by the draw-bars. The improved mechanism is extremely simple and 25 capable of operating efficiently in all the cases which may occur in practice.

Other features will appear from the following description.

In the accompanying drawings which are 30 given by way of example:

Figure 1 is a plan illustrating the draw gear provided with an improved automatic brake apparatus according to this invention.

Fig. 2 is a detailed section drawn to a 35 larger scale, of certain parts shown in Fig. 1.

Fig. 3 is a diagrammatic view of a ratchet gear adapted to be used in combination with the apparatus shown in Fig. 1 for producing a continuous braking.

Fig. 4 is a detailed section of certain parts shown in Fig. 1.

Fig. 5 is a diagrammatic end view of a 40 gear box employed for producing the braking of rearward motion.

Fig. 6 is a corresponding side elevation showing diagrammatically the whole mechanism, and

Fig. 7 is a plan thereof.

Fig. 8 is a horizontal section on the line 55 *b*—*b* of Fig. 10 of one construction of this gear box.

Fig. 9 is a vertical section on the line *c*—*c* of Fig. 8.

Fig. 10 is a vertical section on the line *a*—*a* of Fig. 8.

Fig. 11 is an end view corresponding to Fig. 5.

Fig. 12 is a detailed front elevation of 65 certain parts of the gear box.

Fig. 13 is a corresponding side elevation.

Fig. 14 is a corresponding plan.

Fig. 15 illustrates an elastic mounting of a wheel forming part of the said gear box.

Fig. 16 is a view similar to Fig. 6 showing 70 the connections employed in the case of a single gear box for each vehicle.

Fig. 17 is an end view of a gear box provided with an apparatus for allowing the 75 driver to bring the parts of said box automatically into a disengaged position.

Fig. 18 is a corresponding plan.

As shown in Figs. 1 and 2, a longitudinally movable rod 3 is mounted in a part 80 4 of the car frame behind each buffer rod 1, which carries the buffer head 1^a and is surrounded by the usual buffer spring 2. In a longitudinal recess in the rod 3, is guided a plunger 7 which is normally forced outwardly by a spring 6. The inner end of said 85 plunger may engage the corresponding end wall of the recess in the rod 3, so that when the buffer 1^a is forced inwardly by the buffer of the preceding car when the cars crowd up, the buffer rod will push the rod 3 inwardly through the medium of the spring plunger 7. The rod 3 actuates, either directly or through the medium of a lever 5, a rod 16 provided in the longitudinal direction of the car. Both rods 16, one on 90 each side, are pivotally connected to arms 15 (Fig. 6) which are keyed on the ends of a transverse shaft 25 rotatably mounted in a controlling box shown diagrammatically at 14 in Fig. 6.

The draw-bar 11 which carries the hook 11^a slides in a bushing or sleeve 12 (Fig. 4) and can, through the medium of said sleeve, pull a rod 10 forwardly. A spring 13 is interposed between a head on said rod 10 and 105 the corresponding end wall of the sleeve 12.

The rod 10 is connected at its rear end to a transverse rod 18 connecting to each other two arms 17 keyed on the end of a transverse shaft 26 rotatably mounted in the control box 14.

The construction of the brakes proper is not a part of the present invention. Fig. 6 shows diagrammatically and by way of example, a brake shoe *a* carried by a lever *b* which is pivoted at *c* on the frame and pivotally connected to an operating rod *d'*. In the example shown, the braking action is persistent *i. e.* remains operative when the operating member (buffer or draw-bar) is no more actuated by the corresponding member on the adjacent car. For the purpose of obtaining such persistent braking, an oscillating sector 8 is interposed between the rod *d'* and a corresponding rod *d* and a pawl 9 co-operates with said sector, said pawl being normally held in engagement with the sector by a spring. The pawl can be disengaged from the sector by an oscillating finger 9' actuated by a rod *f*. The rod *d* is connected to an arm 19 keyed on a shaft 27 in the control box and the rod *f* is pivotally connected to the arm 20 keyed on a shaft 28. Both shafts 27, 28 are coaxially arranged in the control box as hereinafter described. They have been shown slightly shifted laterally in Fig. 6 for the sake of clearness.

In the case of forward travel, the shaft 25 is coupled with the shaft 27 as will be shown later on. Consequently, when the buffer is pushed inwardly, by the buffer of the preceding car, the arm 19 is swung and actuates the brake through the medium of the rod *d*, the sector 8 and the rod *d'*. The pawl 9 holds the brake in the set position. On the other hand, the shaft 26 is coupled with the shaft 28 so that when the train speeds up again and the draw-bar is pulled out, the arm 20 is swung and actuates the finger 9'. The pawl 9 is then disengaged by said finger and the brake is released.

For backward travel, the respective actions must be reversed, the brakes being set by the draw-bar and released by the buffer rods. This result is obtained by clutching the shaft 25 of the control box with the shaft 28 and clutching the shaft 26 with the shaft 27. In the example shown, the operative parts of the control 14 are actuated by a motor 21 which may be a compressed air or an electric motor and actuates a lever 22 fixed on a shaft extending into the box. 23 is a spring opposing the action of the motor 21; it allows of employing only one single-acting cylinder or electric motor. 24 are springs for returning at rest, the levers 15, 17, 19 and 20 into a fixed position.

Figs. 8 to 11 show diagrammatically the details of the gear box 14.

The four shafts 25, 26, 27 and 28 are in

one and the same plane. The shaft 25 has permanently fixed on it two wheels 29 and 29'. The shaft 26 has likewise permanently fixed upon it two wheels 30 and 30' which are situated nearer to the axis *x-y* than the wheels 29. The shaft 27 carries a wheel 31, and the shaft 28 carries a wheel 32, each driving the corresponding shaft by means of a key while being able to slide axially along each shaft and thus come into contact either with one of the wheels 29 or with one of the wheels 30. Each of the wheels 29 and the wheels 30 has a notch 33, and each of the wheels 31, 32 has two diametrically situated pins 34. One of these pins, when its wheel comes in contact with a wheel 29 or 30, engages in the corresponding notch in the latter wheel. The notches and pins are so arranged as to face each other when the corresponding shafts and other levers are in the position of rest, which position is fixed and assured by the stops and springs 24 (Fig. 5). The movements of the wheels 31 and 32 in the direction of their axis, are conjugated by means of a bar 35 carrying two forks 36 engaging in circular grooves 37 formed in the hubs of the wheels 31 and 32. The bar 35 slides in two fixed supports parallelly to the axis of the wheels, and this movement assures the conjugated movement of the wheels 31, 32, in such a manner that when one of these wheels is engaged with a wheel 29, the other is engaged with a wheel 30, and vice versa, and also in such a manner that when one of these wheels is situated in an intermediate position, that is to say, is not engaged either with 29 or with 30, the other wheel will be likewise in the same non-engaged position. The movement of the bar 35 is produced by the motor 21 by means of the fork lever 38, shaft 39, and outer lever 22. Finally, the bottom of the box 14 carries a boss 40 (Fig. 10) formed with two inverse helical rams 40' and 40'', and the wheel 32 is provided on its circumference with a roller 41 which rolls over these two ramps during the lateral movements of the wheel 32. The details of this latter arrangement are shown in Figs. 12 to 14. For the clearness of the drawings it is assumed in Figs. 8 to 11 that the motor 21 is at midstroke and the whole of the mechanism is shown in the corresponding intermediate position. But, in reality, owing to the opposing spring 23 (Fig. 11), the only stable positions which the lever 22 can occupy, are the two end positions 22' and 22'', to which correspond the engaged positions of the wheels 31 and 32.

The operation of this apparatus is as follows: Assuming that the motor 21 is not in operation; the spring 23 then holds the lever 22 in the position 22'. The wheel 31 is engaged with the wheel 29', and the wheel 32 is engaged with the wheel 30, that is to 130

say, the rotation of the shaft 27 is due to the rotation of the shaft 25, and the shaft 28 is rotated by the shaft 26. The tightening of the brakes is therefore produced by 5 the buffer plungers, and the release of the brakes is produced by the draw-bar. This is the position for forward travel. When 10 the driver wishes to change over to rearward travel, after having released the air brakes of the locomotive and the tender, and before opening the regulator, he starts the motors 21 by admitting pressure to the pipe supplying said motors. Then on each vehicle the motor 21 moves the lever 22 into 15 the position 22'', and the result is a movement of the two wheels 31 and 32 from right to left. This movement causes first a disengagement of the two wheels 31 and 32 from the wheels 29' and 30 with which they were 20 engaged. This disengagement having been effected, the following operations will now take place:

(a) If all the brake parts are in the position of rest, that is to say, if the buffer springs of the vehicle as well as the draw 25 springs are not compressed the pins of the wheels 31 and 32 and the corresponding notches of the wheels 29 and of the wheels 30 will be situated each in front of the 30 other, the outer levers 15, 17, 19 and 20 (Figs. 5 and 6) being all brought up against their stops by the springs 24. As the movement continues from right to left, the wheel 31 will engage the pin on its left face in 35 the notch of the wheel 30'. As to the wheel 32, its roller 41 will come into contact with the ramp 40'' (Fig. 12) and in rolling over said ramp it will compel the wheel 32 to rotate in the direction of the arrow (Fig. 40 13) then on reaching the other ramp 40' the roller will follow it, and the wheel 32 pulled by the spring 24 acting upon the arm 20 (Fig. 5) will describe an equal angle in the reverse direction, so that the pin on its 45 left face will take up a position in front of the notch of the wheel 29. This pin of the wheel 32 will move into the notch of the wheel 29. The lever 22 will then have the position indicated at 22'', the wheel 31 being engaged with the wheel 30', and the 50 wheel 32 being engaged with the wheel 29; the shaft 27 is driven by the shaft 26 and the shaft 28 is driven by the shaft 25, that is to say, the tightening of the brake is produced by the draw-bar, and the release of 55 the brake is produced by the buffer plungers. This position is that which is suitable for rearward travel.

(b) If the brake is on, and the buffers 60 have remained hard up against one another after having put the brakes on, the wheel 32 in continuing its movement to the left will cause a release of the brake, because by the action of its roller rolling over the ramp 40'', it is caused to revolve to a sufficient

extent to effect the disengagement of the releasing pawl 9 (Fig. 3). As the brake is released, the lever 19, shaft 27 and wheel 31 come into the position of rest, and the pin on the left face of the wheel 31 will be in 70 front of the notch of the wheel 30'. The latter is then likewise in the position of rest because it corresponds with the draw-hook, and the latter is not pulled out. As the movement of the bar 35 and of the wheels 75 31 and 32 continues, the latter wheel, when its roller 41 has moved off the ramp 40', will be returned into a position corresponding to rest, but the notch in the wheel 29 is not situated in front of the pin on the 80 left face of the wheel 32, because the buffers are hard up against each other and the buffer springs are compressed. The said pin therefore butts against the right face of the wheel 29 and the movement is stopped at 85 that point until the occurrence of the first tightening of the brake in backward travel, or until the first movement of the buffers away from each other.

At the time of this first tightening of the 90 brake, the following takes place: As the train travels backward the tightening of the brakes is produced by the draw-bar when its spring is sufficiently compressed, and it is preceded obviously by the opening movement of the buffers and the expansion of the buffer springs. When this expansion has become sufficient, the levers 15, the shaft 25 and the wheels 29 are back again in the 95 position of rest; the notch of the wheel 29 is in front of the pin of the wheel 32 and as the latter is always pushed by the bar 35 owing to the action of the motor 21 which is continuous the pin will become engaged immediately, and thus allow of the engagement 100 of the pin of the wheel 31 which is posted ready in front of the notch of the wheel 30'. The mechanism of the gear box is then in a position adapted for backward 105 travel, and the braking is assured whether it follows immediately or later on.

Nevertheless, in the case of a sudden application of this first braking, notwithstanding the play that is provided (Figs. 1, 2 and 4), and notwithstanding the initial 115 stressing of the buffer springs and the draw-springs, there is the risk that if the draw-hook has already moved to a sufficient extent, the shaft 26 and the wheel 30' will have moved out of the position of rest before the pin of the wheel 31 has been able 120 to engage therein, and the braking, thus produced by a too rapid maneuver, does not take place. In order to provide against the possibility of this danger, the wheel 32 may 125 be fitted with the mechanism shown in Fig. 15. Instead of being mounted directly on the shaft 28, the wheel 32 is mounted on an intermediate sleeve 42 formed with a groove 130 for receiving the fork 36 of the bar 35.

(Fig. 8). Similarly, the sleeve 42 while sharing the rotational motion of the shaft 28, is adapted to slide along the said shaft and along the feather that effects this connection. Similarly, the wheel 32 in rotating carries around with it the sleeve 42 by means of a feather, but it is capable of moving laterally between two collars provided on the sleeve. A spring 43 is interposed between each collar and the corresponding face of the wheel. In short, the wheel 32 instead of being connected rigidly to the groove 37 and consequently to the bar 35 (Fig. 8), is connected elastically to it. At rest, the two springs 43 hold the wheel 32 in a mid position equally distant from the two collars, but if one or the other of the pins 34 of the wheel 32 should encounter any resistance to its motion, in the lateral displacement of the wheel, the wheel 32 is able, by compressing one of the springs 43, to move nearer to the corresponding collar to an extent equal to the length of a pin 34.

If now with a gear box provided with a wheel 32 of this kind, the above description of the engagement in the case (b) be resumed, it will be seen that after the release of the brake has been produced by the wheel 32 rotated by the action of the roller 41 and the ramp 40", the wheel 31 will assume the position of rest, and the pin on its left face will be in front of the notch of the wheel 30' which is itself in the position of rest.

As the bar 35 continues to move from right to left, the pin on the left face of the wheel 32 abuts against the right face of the wheel 29 which is not in the rest position; but as the bar 35 continues its pushing movement, the sleeve 42 (Fig. 15) continues to move and compress the spring 43 on the right hand side, and this movement of the sleeve 42 along the axis of the wheel 32 is sufficient to allow of the pin on the left face of the wheel 31 becoming completely engaged in the notch of the wheel 30'. The proper position for applying the brakes for backward travel is thus immediately assured.

As regards the position of the wheel 32 for releasing the brake, likewise for backward travel, it will be likewise assured in a certain manner before it becomes necessary. As a matter of fact, at the time of the first tightening of the brake which is produced by the movement of the draw-bar, and during the whole period of this tightening, the buffers are moved apart, the shaft 25 and the wheels, 29, are in the rest position, and the pin on the left face of the wheel 32 has all the time that is required for entering the notch of the wheel 29. It will be noted that the spring arrangement shown in Fig. 15, and likewise as well, the actuation by means of a roller and helical ramp shown in Figs. 12-14 which would be difficult to

employ in the case of the wheel 31 owing to the great strains to which the latter is subjected, are on the contrary easy as regards the wheel 32, because this wheel has only to transmit the small strain of disengaging the pawl 9.

(c) If the brake is on and the buffers are apart the brake pressure being maintained solely by the ratchet 8 and the pawl 9 (Fig. 3) after the wheel 32 rotated by the action of its roller 41 and the ramp 40" has disengaged the pawl 9, and the brake has been released, all the wheels will be in position of rest, and the bar 35 continues its movement so that the two wheels 31 and 32 engage their left hand pins immediately into the corresponding notches of the wheels 30' and 29, and thus the position suitable for backward travel, tightening and release of the brakes, is immediately assured.

(d) If the brake is off, and the pawl 9 is kept raised, that is to say, if the buffers are moved apart and the draw-bar is pulled with sufficient force, the shaft 25 and the wheels 29 will be at rest, but the shaft 26 and the wheels 30 are kept in operative position by the pull of the traction bar. In the lateral movement of the wheels 31 and 32 from right to left, the left hand pin of the wheel 31 will therefore not have opposite to it the notch of the wheel 30'. This pin will abut against the right face of the wheel 30' and will there temporarily arrest the motion at that point. When the train starts again, the locomotive pushing it, the draw-bars will be pulled out, and as the shaft 26 comes into the position of rest, the notch of the wheel 30' will come opposite the left pin of the wheel 31 which is still being pulled toward the left of the bar 35, and this pin will engage therein at the same time as the left pin of the wheel 32 will engage in the notch of the wheel 29.

It might be feared that as a consequence of the too rapid compression of the buffers, the left pin of the wheel 32 might not have time to engage in the notch of the wheel 29 before the latter has moved out of its position of rest. The result would be that the pin of the wheel 35 could no longer enter the notch of the wheel 30' and the engagement of the wheels 31 and 30' that is necessary for tightening the brake, would not exist when the action of the draw-bar will cause the shaft 26 to rotate for the purpose of tightening the brake. Likewise as in case (b) hereinbefore described, the apparatus shown in Fig. 15 when applied to the wheel 32 will render such an accident impossible. If, as a result of the too rapid moving away of the notch of the wheel 29, the pin of the wheel 32 should be unable to engage therein, and if this pin abuts against the right face of the wheel 29, this will not prevent the pin of the wheel 31

from engaging completely in the notch of the wheel 30', that is situated opposite, and the position for tightening the brake will be assured immediately. The position for releasing the brake will not be yet assured, but this cannot cause any inconvenience because before the release can take place there must obviously be a tightening of the brake, and during the whole of this tightening the 5 buffer plungers are moved apart, and the shaft 25 with its wheels 29 is in a position of rest. The left pin of the wheel 32, pushed by one of the springs 34 (Fig. 15), has therefore all the requisite time for becoming engaged and the releasing position 10 will be assured before it is required to come into operation.

It might happen that the train may start while the draw-bars are still drawn tight, 20 without the locomotive having to push it. This would take place on a steep incline. The driver is generally notified of this as soon as he has taken off the air brake from the locomotive and the tender, and in such a 25 case, if the backward travel is to be of short duration, the brakes must not be brought into the position for backward travel, but they must be retained in the position for forward travel; then the continuous braking of the train would be produced by the 30 braking of the last vehicle, exactly as in the brake of a detached portion of the train. Nevertheless, if, owing to inadvertence, or 35 in view of prolonged backward travel, the driver has admitted pressure to the train pipe for the purpose of producing the backward travel position of the brakes, the immediate taking up of this position can be 40 effected without awaiting the end of the gradient by means of the following operation.

The last vehicle is braked solely. The other vehicles will crowd up against it one after the other and as the draw-hooks 45 come loose, the shaft 26 will come into the position of rest, and the wheel 31 can engage with the wheel 30'. When the whole train or a sufficient portion of the train has been crowded up, the brakes on the last vehicle 50 are taken off.

All the cases that may occur in passing from the forward travel position to the backward travel position have been dealt with, but the normal case is the case (b), 55 that is to say the brakes being on, and the buffers hard up against each other. It will be noted that in this case as in the case (c) and especially when the motors 21 are driven by compressed air, the release of the 60 brakes will take place along the train from the vehicles following the tender and thus assure starting with jolts. It will also be noted that in the case of braking a detached portion of the train during backward travel, 65 the gear boxes 14 will assume automatically

the forward travel position for braking the said detached portion by crowding the vehicles up against the last vehicle which is provided with a separate brake.

When the gear boxes are in the position 70 for backward travel and are held in this position by the motors 21, and if the driver should wish to change them over into the position for forward travel, he discharges the pneumatic or electric train pipe feeding 75 the motors 21. As the motive action ceases, the lever 22 (Fig. 5) is returned by the spring from the position 22" into the position 22'. This motion transmitted to the bar 35 and to the wheels 31 and 32, has the 80 first result of disengaging the wheels 31 and 32 from the wheels 30' and 29, with which they are in engagement. The movement of the wheels 31 and 32 being continued from left to right, the series of operations will be 85 readily understood according as the cases (a'), (b'), (c'), (d') occur, said cases corresponding to the cases (a), (b), (c), (d), hereinbefore described, of the change to backward travel. The following is a short 90 summary:

(a') Brakes off, the draw springs and the buffer springs not deformed, or only very slightly deformed; all the corresponding parts of the gear box are in the position of 95 rest; the complete coupling for forward travel is effected at once.

(b') Brakes on, the draw hooks pulled out, and the draw springs deformed; this case corresponds with the case (b), and is 100 the normal case, occurring after a stoppage, by braking, of the backward travel.

1. Disengagement of the releasing pawl 9 by the action of the wheel 32 and tightening 105 of the brake.

2. Stoppage of the sliding movement of the wheel 32 by its right pin which abuts against the full portion of the wheel 30. But if the wheel 32 is fitted with the mechanism shown in Fig. 15, the bar 35 and the 110 wheel 31 will, however, still continue their sliding movement, and the wheel 31 will engage with the wheel 29', thus assuring the position for tightening the brake.

3. At the time of the first tightening of the 115 brake, the wheel 32 engaging with the wheel 30, the connection is complete.

(c') The brakes on, the draw springs not deformed and the brake being only maintained by the ratchet 8 and the pawl 9 (Fig. 120 3). The wheels 29 and the wheels 30, and the wheel 32 are in a position of rest. As soon as the brake is released by the disengagement of the pawl 9 by the action of the wheel 32, the shaft 27 and the wheel 31 125 will return into their position of rest, and the engagement of the wheels 31 and 29', 32 and 30 may take place; the connection is at once complete.

(d') Brakes off, the buffers hard up against 130

each other and maintaining the pawl 9 in its position of rest:

1. The shaft 25 and the wheels 29 not being in a position of rest, the right pin of the wheel 31 will abut against the full portion of the wheel 29'.

2. The train on starting being pulled by the locomotive, the buffers move apart and thus allow the immediate engagement of the wheel 31 with the wheel 29', this engagement being rendered certain by the mechanism shown in Fig. 5. The engagement of the wheel 32 with the wheel 30 takes place at the same time or it takes place during the next following first putting on of the brakes. If the train in starting on a steep gradient pushes the locomotive, the buffers will not move apart and the wheels 31 and 29' are unable to engage. In such a case the moving part of the buffers and the engagement of the wheels 31 and 29' are effected, by starting with the brake put on on the last vehicle, or by braking this last vehicle as soon as the starting has taken place. Or again, before placing the brakes in the position for forward travel, the locomotive brake may be released, while maintaining the continuous brake engaged in its position for backward travel, and braking the last vehicle, which will cause the whole train to be braked and to be stopped, the draw-bars being pulled out. The train pipe for the continuous braking will then alone be discharged, and the engagement for forward travel will take place as in the case (b').

It will be noted that more particularly with compressed air working, the release of the brakes in the case (b') and (c') will take place gradually from the first vehicle to the last vehicle of the train, thus readily allowing of starting without jolting.

From the foregoing the operation of the gear box can take place during travel for the purpose of effecting a release of the brakes before it is produced by the action of the draw-bars or of the buffer plungers. This might be useful in certain cases, for instance for facilitating rapid picking up after braking, and a special device for effecting this is hereinafter described. On the other hand, it has been noted that the ratchet (Fig. 3) may be so designed as to enter into engagement only after a certain amount of braking has taken place, so that light brakings are therefore not continuous.

It is also to be noted that the mechanism shown in Fig. 15 may be replaced by an apparatus which will allow of a lateral movement of each pin of the wheel 32 relatively to the latter, which will then remain fixed immovably on its hub.

The gear box hereinbefore described is applicable to the case of brakes operating with continuous pressure. In the case of non-continuous pressure brakes, the ratchet

8 and the pawl 9 are omitted, as well as the corresponding parts of the gear box, namely wheel 32, wheel 29, wheel 30 and ramps 40' and 40''. The operation of the box thus simplified is similar to that which has been described in each of the cases (a), (b), (c), (d) and (a'), (b'), (c'), (d') the brake assuming automatically its position of release as soon as the wheel 31 is disengaged, either from the wheel 29' or from the wheel 30'.

Two gear boxes may be provided on each vehicle, each actuating the rodding of one axle or of one bogie, and operated respectively by the draw-bar and the pair of buffers of the corresponding end of the vehicle; this is the case of the gear box shown in Figs. 5 to 7. Or all the brake blocks of the vehicle may be operated by a single gear box controlled both by the front draw gear and the back draw gear of the vehicle. Fig. 16 is a diagrammatic view of the external connections of a single gear box of this kind.

The levers 15 and 17 of Fig. 6 are extended beyond the shafts 25 and 26 which they control, by levers 15' and 17' and these extensions are pivoted to the rods 16' and 10' leading to the buffer plungers and the draw-bar at the other end of the vehicle. Guide slots 44 are provided for the pivots of the rods 16 and 16', 10 and 10', connecting with the levers which they actuate, in such a manner that these rods pull the levers only in the direction of the action that corresponds to the pull of the rods, and they cannot be pulled by the levers except likewise in the direction of the pull. These guide slots are not indispensable because (Figs. 1 and 2) the connection between 1 and the end 7 of the member 3 takes place only in one direction, and similarly the connection between 11 and 10 (Figs. 1 and 4) takes place only in one direction, at least within the limits of the play in the interior of 12 between the heads of the rods 11 and 10. This play, being determined by the action of the ratchet 8 (Fig. 3) would likewise be sufficient to allow of a free movement of the rod 10 by the action of the movement of the rod 10', respectively of the position of the bar 11.

Nevertheless, the guide slots 44 prevent useless movements of the rods that are not working, and thus diminish the inertia of the entire system. Moreover, they prevent the rods 10 and 10', 16 and 16' from being strained compressively and consequently allow of their section being reduced.

It has been stated that for the purpose of allowing of handling single vehicles, it was necessary to provide a disengaging mechanism between the brakes and their operating parts. Now, in the gear box which is described (Figs. 8 to 11), when

the lever 22 is in mid position between its two end positions, this disengagement is effected. This is the position shown in Figs. 8 to 11. The brake is there shown released by the previous action of the wheel 32 and the ramps 40' and 40'' (Figs. 12 to 14), and its driving wheel 31 is disengaged likewise from the action of the buffer plungers and the draw-bar.

10 Therefore in order to disengage the brake, it will be sufficient to move the lever 22 into its mid position and to maintain it in that position during the whole time that the brake is to be locked in the rest position.

15 The automatic control by the driver, of this position of disengagement might be provided. In view of the fact that the handling of single vehicles, as well as the fly-shunting of same on sorting tracks, is effected almost always by pushing and not pulling said vehicles, the gear box shown in Fig. 6 might be simply adapted for the purpose, by placing the position for forward travel in dependence on the action of 20 the motor 21, instead of leaving it in dependence on the opposing spring 23. The single vehicle would therefore have its gear box in the position for backward travel, and would be moved along by pushing without 25 causing its brakes to come into operation.

30 A preferred form of apparatus for permitting automatic control by the driver without supplementary parts or pipes will now be described.

35 This apparatus which is carried by the face of the gear box opposite to that provided with the motor 21 and by the upper face of said box, is illustrated in Figs. 17 and 18 which are respectively a front view 40 of the box 14 and a plan of its upper part.

45 The interior of the gear box is the same as that shown in Fig. 6 with the exception of one modification, namely, the shaft 39 has been extended beyond the fork lever 38, and

50 it projects at the opposite face to that of the lever 22 where it receives a lever 45 (Fig. 17) that is fixed on it and is guided toward its upper part by an arc-shaped slot 46. One of the two end positions 45' or 45'' is occupied by the lever 45 when the lever 22 (Fig. 11) occupies the corresponding position 22' or 22'', and when 55 the lever 22 is situated in the mid position corresponding to the disengagement of the brake, the lever 45 will also be equally distant from its two end positions. This position of the lever 45 is shown in Fig. 17.

60 The lever 45 and consequently the entire mechanism of the gear box is held in this mid position by a spring pawl 47 that engages a stud 48 fixed on the lever. The pawl 47 is formed with a tail 49 and its movement is limited by the stop 50. When 65 the pawl 47 is at rest, lying against its stop 50, if the lever 45 starting from the

position 45' is moved toward 45'' by the action of the motor 21, it will meet the head of the pawl 47, and in continuing its movement it will push it back toward the right until the stud 48 sliding over the nose of the pawl 47, engages with its underside. The lever 45 is then in its mid position, and if the action of the motor 21 ceases at this moment, the lever 45 is held in this position by the pawl 47 and will thus oppose the return to the rear of the whole mechanism pulled by the opposing spring 23 (Fig. 11). If the action of the motor 21 continues beyond the mid position, the lever 45, or rather its stud 48, acting upon the body of the pawl 47, will push the latter toward the right. But when the action of the motor 21 ceases, the pawl 47 pushed by its spring, follows the stud 48, and arrests again the lever 45 in its mid position. However, if the motor 21 acts until the lever 45 has reached the position 45'', the pawl 47 will be sufficiently pushed back to the right to enable its tail 49 to engage with the underside of the nose of the spring 90 pawl 51, the prolonged end of which is guided by the slot 52 and bends then over the gear box. From this moment onward the pawl 47 being held, is no longer able to follow the stud 48 in the rearward movement of the lever 45, and the latter can then move freely within the area comprised between 45' and 45'', without affecting the pawl 47. It will therefore be seen that whether a start is made from the initial 100 position, that is to say, with the pawl 47 free and bearing against its stop, or whether a start is made from the normal position, that is to say, with the pawl 47 held by the pawl 51, the actuation of the gear box 105 14, both for forward travel and backward travel, will be effected without being interfered with by the pawl 47.

If, on the contrary, the nose of pawl 47 being freed from the pawl 51, the lever 45 be caused to describe from 45' one half only of the sector 45'-45'', or a little more than half, the said lever will not be able to return toward 45' from its mid position because it is engaged by the pawl 47. To 110 free the pawl 47 it will then be sufficient to move it from its mid position as far as 45'', which movement by engaging the pawl 47 with the pawl 51, will allow it to return 115 freely to 45' under the action of the opposing spring 23.

This allows of disengaging and reengaging the brake on a separate vehicle at will. The action of the motor 21 is replaced by the action of two sliding bolts 53 and 125 54 operated from the ground on each side of the vehicle by means of two handled chains 55-56 and 57-58 acting through the medium of levers 59 and 60 and under the counter-action of two springs 53' and 130

54'. The first sliding bolt 53 is, together with stops 61 and 61', adjusted in such a manner that during its movement, its nose 62 (which is situated at rest outside 5 of the sector 45'-45'') will push the end of the lever 45 and thus move the latter slightly beyond its mid position, so that its end 63 strikes against the bent extension 10 of the pawl 51, shifts it toward the right, and causes the disengagement of the pawl 47. The disengagement of the brake is then effected and the sliding bolt 53 moved back by the spring 53', returns into its initial position ready for a fresh disengagement. 15 The second sliding bolt 54 produces the reengagement in the position of forward travel (tightening the brake by compression of the buffer springs). For this purpose its stops 64 and 64' are so adjusted 20 that during its movement its nose 65 (which at rest is situated outside the sector 45'-45'') shall push the lever 45 into the position 45'', and its end will pass clear of it above the extension of the pawl 51. The 25 pawl 47 has thus become engaged by the pawl 51, and the lever 45 can be returned by the spring 23 into the position 45' (forward travel).

To facilitate the operation still further, 30 the lever 45 actuates, by means of two ropes or rods 66 and 66', two devices for indicating the position of the brake, one on each side of the vehicle.

By adding a device for locking the sliding 35 bolt 54 at the end of its operative stroke, it would be possible also to lock the lever 45 in the position 45'', and to assure likewise at will on the isolated vehicle the backward travel position of the braking apparatus. 40 But, in general, this is not necessary because the two positions, disengagement and forward travel, are sufficient for all usual maneuvers. As a matter of fact in the disengaged position, the vehicles either singly 45 or in batches can be both pulled and pushed, and likewise by the easy and rapid operation of one of the chains 57 or 58, the forward travel position can be reestablished in such a manner that the single vehicle or the batch 50 of vehicles will put their brakes on automatically on arriving at the stop or against the batch of vehicles already in place. In the case of a fresh handling of the vehicles a pull upon the chains 57, 58 will produce 55 through the medium of the sliding bolt 54 a simple release of the brake with its immediate return into the forward travel position. A pull upon the chain 55-56 will assure the release of the brake and place it in 60 the disengaged position. Similarly, during the marshaling or sorting maneuvers when the vehicle or a batch of vehicles has been detached from the train, the brakes will place themselves immediately in the forward 65 travel position without being on. If the

sorting is effected by gravity, they are left in this position and the brake blocks will tighten when the vehicles arrive at the fixed stop, or by pulling the chain 55-56 as soon as the vehicle has been detached or even before, they can be placed in the disengaged position. 70 If the sorting is done by fly-shunting, obviously except in the case of automatic couplings, the vehicles must be placed in the disengaged position (this may be done as hereinafter described automatically by the driver for the purpose of accelerating the maneuver when it is desired to fly-shunt a batch of vehicles). When the vehicles have been fly-shunted, they can be 80 left in the disengaged position or they can be placed in the forward travel position by acting upon the chain 57-58, and then the vehicles will brake themselves on arriving at the stop. 85

As shown in the foregoing, if the pawl 47 is in the position illustrated in Fig. 17, that is to say, freed from the pawl 51, when the lever 45 starts from the position 45' by the action of the motor 21, the lever 45 has 90 its stud 48 engaged by the pawl 47 immediately it has passed the mid position, and this stud remains engaged so as to arrest the lever on its return in the mid position, so long as this lever has not reached a position 95 very near to 45'', in which position the tail 49 of the pawl 47 is engaged by the pawl 51. The driver would then have it in his power to cause the lever to come automatically into its mid position if the said lever 45 should 100 on starting from 45', find the pawl 47 freed from the pawl 51. This condition will be brought about by providing the lever 45 with a heel-piece 67, and by providing the pawl 51 with a tail 68 as indicated in dot 105 and dash lines in Fig. 17. When the lever 45 occupies the position 45', its heel 67 will raise the tail 68 and thus move the pawl 51 to the right, thereby freeing the pawl 47. The heel 67 should move away from the tail 110 68 after a slight movement of the lever 45, in any case before the latter reaches the mid position. These two parts 67 and 68 will not in any way interfere with the functions 115 which the pawls 47 and 51 have already performed, and this will even allow of omitting on the upper face of the gear box the extension of the pawl 51 which will no longer require to be disengaged by the end of the sliding bolt 53. The positions 45', forward 120 travel, and 45'', backward travel, will then be obtained as before by charging or discharging the train pipe. The mid position "disengagement" will be produced automatically by placing the train pipe under half 125 pressure in such a manner as to enable the motor 21 to move the lever into the mid position, while however its action is balanced, slightly beyond that position, by the increasing tension of the opposing spring 23. When 130

the train pipe consists of an electric main, it will be sufficient therefore to reduce the voltage if the supply is taken from a shunt circuit, or to interpose a resistance if the supply is in series. When the motor is driven by air pressure, it will be sufficient to charge the train pipe through the medium of a suitably adjusted pressure-reducing device.

10 When the electric power is supplied from a shunt circuit there is a drop in voltage from the first vehicle to the last vehicle of the train, and in the case of a pneumatic train pipe there is a fall in pressure even 15 when the permanent working is established because the delivery is not *nil*, for instance on account of leakage; but the distance between the mid position at which engagement by the pawl begins, and the position at 20 which it finishes owing to the engagement of the pawl 47 by the pawl 51, gives a margin that is amply sufficient to make up for these losses in the air pressure.

The operation of the brakes, instead of 25 being assured by the existing connecting members, namely the buffer plungers and draw-bars, may also be effected by a special connecting member between the vehicles.

Having now described my invention what 30 I claim as new and desire to secure by Letters Patent is:

1. A brake installation for railway vehicles, comprising the combination of brakes, actuating means for said brakes, a buffer 35 plunger, a draw-bar and a clutch mechanism controlled by the driver and adapted to operatively connect the said actuating means either with the buffer plunger or the draw-bar, whereby the said actuating means 40 are operated by the buffer plunger when traveling forward and by the draw-bar when traveling backward.

2. A brake installation for railway vehicles, comprising the combination of brakes, 45 actuating means for said brakes, a buffer plunger, which is normally in operative connection with the said actuating means, a locking mechanism adapted to keep the brake on, a draw-bar, which is normally in 50 operative connection with the locking mechanism and a clutch mechanism controlled by the driver and adapted to interchange the connections between the buffer plunger and the draw-bar on the one hand and the said 55 actuating means and the locking mechanism on the other hand.

3. A brake installation for railway vehicles, comprising the combination of brakes, actuating means for said brakes, a buffer 60 plunger, a rod operatively connected to said buffer plunger, an oscillating shaft adapted to be operated by said rod, two notched wheels carried on said shaft, a draw-bar, a rod operatively connected to said draw-bar, a 65 rod operatively connected to be operated

by said rod, two notched wheels carried on said shaft, two transmitting shafts, two pin wheels splined on said shafts respectively and adapted to engage with the notched wheels, means for operatively connecting 70 one of said transmitting shafts to the brake actuating means, a locking mechanism adapted to keep the brakes on, means for operatively connecting the other transmitting shaft to said locking mechanism, and 75 means controlled by the driver for axially moving both of said pin wheels along their respective shafts to engage the same with the notched wheels or disengage the same therefrom, substantially as described and 80 for the purpose set forth.

4. A brake installation for railway vehicles, comprising the combination of brakes, actuating means for said brakes, a buffer plunger which is normally in operative connection with the said actuating means, a locking mechanism adapted to keep the 85 brakes on, a draw-bar which is normally in operative connection with the locking mechanism and a clutch mechanism controlled by 90 the driver and adapted to interchange the connections between the buffer plunger and the draw-bar on the one hand and the said actuating means and the locking mechanism 95 on the other hand, said clutch mechanism embodying means whereby in the operation of the clutch mechanism, the brakes are first released if they were on.

5. A brake installation for railway vehicles, comprising the combination of brakes, 100 actuating means for said brakes, a buffer plunger, a rod operatively connected to said buffer plunger, an oscillating shaft adapted to be operated by said rod, two notched wheels carried on said shaft, a draw-bar, a 105 rod operatively connected to said draw-bar, an oscillating shaft adapted to be operated by said rod, two notched wheels carried on said shaft, two transmitting shafts, two pin 110 wheels splined on said shafts, respectively and adapted to engage with the notched wheels means for operatively connecting one of said transmitting shafts to the brake actuating means, a locking mechanism adapted to keep the brakes on, means for 115 operatively connecting the other transmitting shaft to said locking mechanism, a fixed cam adapted to impart a rotation to the pin wheel on said last mentioned transmitting shaft when said wheel is displaced 120 axially, whereby in the operation of the clutch mechanism, the brakes are first released if they were on, and means controlled by the driver for axially moving both of the pin wheels along their respective shafts to 125 engage the same with the notched wheels or disengage the same therefrom substantially as described and for the purpose set forth.

6. A brake installation for railway vehicles, comprising the combination of 130

brakes, actuating means for said brakes, a buffer plunger, a rod operatively connected to said buffer plunger, an oscillating shaft adapted to be operated by said rod, two notched wheels carried on said shaft, a draw-bar, a rod operatively connected to said draw-bar, an oscillating shaft adapted to be operated by said rod, two notched wheels carried on said shaft, two transmitting shafts, two pin wheels splined on said shafts, respectively and adapted to engage with the notched wheels, means for operatively connecting one of said transmitting shafts to the brake actuating means, a locking mechanism adapted to keep the brakes on, means for operatively connecting the other transmitting shaft to said locking mechanism, a fixed cam adapted to impart a rotation to the pin wheel on said last mentioned transmitting shaft when said wheel is displaced axially, whereby in the operation of the clutch mechanism, the brakes are first released if they were on, means for yieldingly supporting said last mentioned wheel in an axial direction on its transmitting shaft and means controlled by the driver for axially moving both of the pin wheels along their respective shafts to engage the same with the notched wheels or disengage the same therefrom, substantially as described and for the purpose set forth.

7. A brake installation for railway vehicles, comprising the combination of brakes, actuating means for said brakes, buffer plungers at both ends of the vehicle, a locking mechanism adapted to keep the brakes on, draw-bars at both ends of the carriage, and a single clutch mechanism controlled by the driver and adapted to interchange the connections between the buffer plungers and the draw-bars on the one hand and the said actuating means and the locking mechanism on the other hand.

8. A brake installation for railway vehicles, comprising the combination of brakes, actuating means for said brakes, a buffer plunger which is normally in operative connection with the said actuating means, a locking mechanism adapted to keep the brakes on, a draw-bar which is normally in operative connection with the locking mechanism, a clutch mechanism adapted to interchange the connections between the buffer plunger and the draw-bar on the one hand and the said actuating means and the locking mechanism on the other hand, an operating oscillating lever for said clutch mechanism adapted to assume three angular positions, the two extreme positions corresponding to interchanged connections between the above mentioned parts and the medium position corresponding to inoperative connections, means controlled by the

driver for operating said lever, a retaining device adapted to hold the said lever in its medium position and hand controlled means for operating said lever.

9. A brake installation for railway vehicles, comprising the combination of brakes, actuating means for said brakes, a buffer plunger which is normally in operative connection with the said actuating means, a locking mechanism adapted to keep the brakes on, a draw-bar, which is normally in operative connection with the locking mechanism, a clutch mechanism adapted to interchange the connections between the buffer plunger and the draw-bar on the one hand and the said actuating means and the locking mechanism on the other hand, an operating oscillating lever for said clutch mechanism adapted to assume three angular positions, the two extreme positions corresponding to interchanged connections between the above mentioned parts and the medium position corresponding to inoperative connections, means controlled by the driver for operating said lever, a retaining device embodying, a retaining pawl adapted to hold the said lever in its medium position, a controlling pawl adapted to hold the retaining pawl in an inoperative position and means for releasing said controlling pawl.

10. A brake installation for railway vehicles, comprising the combination of brakes, actuating means for said brakes, a buffer plunger, which is normally in operative connection with the said actuating means, a locking mechanism adapted to keep the brakes on, a draw-bar, which is normally in operative connection with the locking mechanism, a clutch mechanism adapted to interchange the connections between the buffer plunger and the draw-bar on the one hand and the said actuating means and the locking mechanism on the other hand, an operating oscillating lever for said clutch mechanism adapted to assume three angular positions, the two extreme positions corresponding to interchanged connections between the above mentioned parts and the medium position corresponding to inoperative connections, means controlled by the driver for operating said lever, a retaining device embodying, a retaining pawl adapted to hold the said lever in its medium position, a controlling pawl adapted to hold the retaining pawl in an inoperative position, means for releasing said controlling pawl and a hand controlled member adapted to bring the oscillating lever to one of its extreme operative positions.

In testimony whereof I have signed my name to this specification.

PIERRE FRANCOIS DUFOUR.
